UNITED STATES PATENT OFFICE

108,709

DESIGN FOR A HANDLE FOR A HAMMERING TOOL

Sanford S. Vaughan, Oak Park, Ill., assignor to
Vaughan & Bushnell Mfg. Co., Chicago, Ill., a
corporation of Illinois

Application September 27, 1937, Serial No. 71,808

Term of patent 14 years

To all whom it may concern:

Be it known that I, Sanford S. Vaughan, a citizen of the United States, residing at Oak Park, in the county of Cook and State of Illinois, have invented a new, original, and ornamental Design for a Handle for a Hammering Tool, of which the following is a specification, reference being had to the accompanying drawing forming a part thereof.

Figure 1 of the drawing is a side view of a handle for a hammering tool, showing my new design;

Figure 2 is a plan view of the handle; and

Figure 3 is a transverse sectional view on the line 3—3 of Figure 1.

The characteristic features of my design reside in a handle of the configuration shown, having on its reduced neck portion of elliptical shape a series of four spaced apart longitudinally extending flutes; said flutes being semi-circular in section and of a width equal to substantially one-fifth the major axis of the elliptical neck portion at its smallest diameter and extending in length substantially the full distance of said reduced neck portion.

I claim:

The ornamental design for a handle for a hammering tool substantially as shown and described.

SANFORD S. VAUGHAN.
